United States Patent Office.

ROBERT BROWN, OF NORWICH, CONNECTICUT.

Letters Patent No. 80,592, dated August 4, 1868.

IMPROVEMENT IN STEAM-TRAPS.

The Schedule referred to in these Letters Patent and making part of the same.

TO ALL WHOM IT MAY CONCERN:

Be it known that I, ROBERT BROWN, of Norwich, in the county of New London, and State of Connecticut, have invented a new and improved Steam-Exhaust Device; and I do hereby declare that the following is a full, clear, and exact description thereof, which will enable those skilled in the art to make and use the same, reference being had to the accompanying drawings, forming part of this specification.

The object of this invention is to so construct a steam-valve movement for the exhaust of the steam that it shall be self-acting, and moved exclusively by the pressure of the steam.

And it consists in two disk-valves, upon a rod, operating in a partitioned exhaust-steam chest, connected with the cylinder, whereby the engine-cylinder is relieved of under pressure at its exhaust-end, and also of the water of condensation, in the manner hereinafter described.

The drawing,

Figure 1, represents the arrangement, in connection with a steam-engine cylinder, the latter, with the steam-pipes, being shown in red.

Figure 2 is a transverse section, showing one of the valve-seats and the steam-chest.

Similar letters of reference indicate corresponding parts.

A is the steam-exhaust chest, which is attached to the cylinder, and divided into three compartments, as seen in the drawing.

These compartments are marked B, C, and D.

C is the chamber, to which the exhaust-pipe E is attached.

The partitions F and G are the valve-seats.

H and I are the valves, and

J is the rod, to which the valves are attached.

Each end of this chest is connected with the ends of the engine-cylinder, as seen in the drawing.

When steam is admitted to the cylinder to drive the piston to the right, as indicated by the arrow, the left-hand end of the cylinder is full of steam, which passes into the exhaust-cylinder and compartment B, and closes the valve H to the seat F, as seen, while the steam from the other (or right-hand end of the cylinder) is exhausting through the valve-seat G.

In the drawing, fig. 2, it will be seen that the valve-seats have orifices, i, for the passage of steam into the compartment C, which orifices are opened and closed alternately as the valves are moved.

When the motion of the piston is reversed, and steam is admitted into the right-hand end of the cylinder, the motion and position of the valves will be reversed—I will be closed and H opened.

Before the piston has reached the limit of its movement in either direction, the steam from the boiler is cut off by any suitable mechanism, and the piston completes the remainder of its stroke by the expansive force of the steam in the cylinder, as in ordinary cases.

It will be seen that the pressure upon the valves I and H is the same as that upon the sides of the piston of the engine, and that the ends of the cylinder are relieved of the water of condensation at every stroke of the engine.

As the present invention relates only to the exhaust of the steam, and preventing the water of condensation from interfering with the working of the engine, it has not been deemed necessary to show or describe the slide or operating-valve movement of the engine.

In this exhaust-arrangement, the valve-rod J slides through the partition-plates F and G.

The valves H and I are attached to its ends, and are made of less diameter than the chest A, so that they occasion no friction in their movement, excepting in the partition-plates.

I am aware of the patents granted to Allen Lapham, September 23, 1862, and to H. J. Vaerson, June 14, 1864, for improvements in steam-traps, but as these contain no part of my improvement I do not, therefore, claim them.

Having thus described my invention, I claim as new, and desire to secure by Letters Patent—

The arrangement of the steam-exhaust chest A, the perforated partitions F G, the disk-valves H I, and their common stem, J, with relation to each other and the cylinder, as herein shown and described.

ROBERT BROWN.
